UNITED STATES PATENT OFFICE.

HERBERT J. HOPE, OF SANFORD, MAINE.

PILE-FAIRY LOOM.

1,298,949.

Specification of Letters Patent.

Patented Apr. 1, 1919.

Application filed August 31, 1917, Serial No. 189,055. Renewed February 3, 1919. Serial No. 274,801.

To all whom it may concern:

Be it known that I, HERBERT J. HOPE, a citizen of the United States, residing at Sanford, county of York, State of Maine, have 5 invented an Improvement in Pile-Fabric Looms, of which the following description, in connection with the accompanying drawing, is a specification, like characters on the drawing representing like parts.

10 This invention relates to pile fabric looms and has for its object to provide novel means for automatically controlling the wire motion so that it may be made to skip or fail to withdraw and insert a wire at predetermined picks, thus enabling a figured pattern to be woven. In the operation of a pile fabric loom wherein the pile is produced by pile wires, the failure to insert a pile wire at one or more successive picks will result in 15 the formation of a plain weave without the pile, and by arranging a mechanism whereby the wire motion will operate to skip at intervals for one or a plurality of successive picks, a fabric will be woven in which the 20 surface is partly a pile surface and partly a plain woven surface. If in addition the harness frames controlling the pile warps are actuated by a suitable pattern mechanism a highly-figured fabric may be produced.

25 My present invention provides means for automatically controlling the wire motion so as to cause it to skip or fail to insert and withdraw a wire at predetermined intervals, thus permitting the production of the fancy or figured fabric, as above described.

30 In order to give an understanding of my invention, I have illustrated in the drawings a selected embodiment thereof which will 40 now be described, after which the novel features will be pointed out in the appended claims.

Figure 1 is a plan view of a portion of a pile fabric loom embodying my invention; 45 Fig. 2 is a side view of one of the pile wires showing its head;

Fig. 3 is a section on the line 3—3, Fig. 1.

I have shown herein a portion only of a pile fabric loom as it is not necessary to 50 illustrate the complete loom in order to gain an understanding of the invention.

55 1 indicates a portion of the frame or stand of the loom which supports or contains the magazine 2 for the pile wires, and each pile wire 3 is formed with the head 4 having a slot 5 formed therein for the re-

ception of the withdrawing hook, all as usual.

6 indicates the wire guide which receives and guides the wires as they are being inserted into the shed. 7 is the usual carriage which is mounted for reciprocation upon guides or ways 8 and which is constructed to introduce the wires successively into the shed and is provided with the usual with- 60 drawing hook 9 that is adapted to engage in the slot 5 of the head of each wire and withdraw the wire. The slide 7 is connected by a link 10 to a reciprocating arm or actuator 11, all as usual in pile wire motions. 70

The magazine 2 is provided with a follower 12 which is pivoted at 13 and is acted upon by a suitable spring 14, said spring having the function of holding the follower 12 yieldingly against the head of the wire 75 which has been last inserted.

The parts which have thus far been described are or may be all as usual in pile wire motions of pile fabric looms, and in the operation of the loom a wire is inserted into 80 the shed by the carriage 7 when the latter moves toward the left, Fig. 1, said wire being guided into position by the wire guide 6, and when in proper position having its head engaged by the yielding follower 12. 85 In Fig. 1 I have shown the carriage nearly at the end of its wire-inserting movement. As the carriage completes such movement, the withdrawing hook 9 wipes over the side of the pile wire head 4 which rests against 90 the wall 15 of the magazine and drops into the slot 5 thereof so that upon the backward movement of the carriage 7, the foremost wire is withdrawn from the fabric. At the next movement of the carriage 7, this wire 95 will be introduced into the shed through the guide 6.

I have provided herein means which operate automatically at predetermined times to prevent the withdrawing hook 9 from engaging a pile wire head when the carriage completes its wire-inserting movement with the result that at such times the carriage will make its wire-withdrawing movement without withdrawing a wire from the fabric, and hence will make its next wire-inserting movement without inserting a wire in the shed. The automatic means which I have herein illustrated for thus causing the withdrawing hook to skip is in the nature of 100 pattern mechanism so that the skipping operation of the withdrawing hook will be 105

produced at such times as is called for by the pattern which, of course, will depend upon the figure that it is desired to produce in the fabric. While any suitable pattern mechanism for thus controlling the operation of the withdrawing hook may be employed without departing from my invention, as I believe I am the first to provide automatic or pattern-controlled means for this purpose, 10 I have illustrated herein a simple and efficient device.

Pivottally mounted at 17 on the carriage 7 is a two-armed lever 16, one arm 18 of which is offset to enter an aperture 19 in the carriage and engage the withdrawing hook. The other arm 20 of the lever 16 is provided with a beveled or cam surface 21 which is adapted to engage a pattern-controlled element 22 as the carriage completes its forward movement. This element 22 is herein shown as a pin slidably vertically in the frame 1 and acted upon by a spring 23 which tends to hold the pin in its lowered position. The lower end of the pin is acted on by a pattern chain 24 which operates over an actuating sprocket 25 that may be driven from any convenient moving part of the loom so that it will rotate in timed relation with the operations of the loom. The pattern chain 24 is shown as having appropriately-situated risers 26 thereon. As the pattern chain is actuated, the risers 26 will engage the lower end of the pin 22 and raise the same against the action of the spring 23, and as soon as 35 any riser has passed out from beneath the pin, then the spring 23 will lower the pin into its full line position. The pin is so constructed that when it is in its lowered or full line position, it is withdrawn from the 40 path of movement of the finger 20, and as a result, when this condition exists, the withdrawing hook 9 will operate to withdraw a pile wire from the fabric upon its backward movement and to insert said pile wire into 45 the shed again upon its next forward movement. When, however, a riser 26 has been brought into position to elevate the pin 22, then when the carriage completes its wire-inserting movement, the cam end 21 of the 50 arm 20 will engage the elevated pin 22, thus swinging the lever about its pivot 17 and causing the offset portion 19 of the arm 18 to move the withdrawing hook 9 into the dotted line position, Fig. 1, in which position 55 it does not engage the head of any of the pile wires in the magazine. As a result, the withdrawing hook will fail to withdraw a pile wire from the fabric upon its return movement, and as no wire has been withdrawn, 60 there will be no wire to insert on the next forward movement of the carriage 7. If at

the end of the next forward movement, the pin 22 is still elevated by another riser, then the withdrawing hook will again fail to withdraw a pile wire and will also again fail 65 to insert a pile wire. On the other hand, if the pin 22 is not elevated by a riser, then the withdrawing hook will be operative to withdraw a pile wire, as usual. The fabric which is thus woven will have a surface which is 70 partly a pile surface and partly a plain surface, the proportions depending upon the character of the pattern mechanism.

I claim:

1. In a pile fabric loom of the type having 75 means for withdrawing from the fabric being woven a pile wire that has been woven therein and then inserting said pile wire in an open shed, pattern mechanism to render inoperative at predetermined times the said 80 means for withdrawing a pile wire whereby at such times no pile wire will be inserted into the shed and a pattern will thereby be produced in the fabric.

2. In a pile wire loom of the type having 85 a reciprocating carriage adapted during its movement in one direction to withdraw from the fabric a pile wire that has been woven therein and upon its next succeeding movement in the other direction to insert said pile 90 wire into an open shed, pattern mechanism operative at predetermined times to cause said carriage to fail to withdraw a pile wire during its wire-withdrawing movement whereby a pile wire will not be inserted at 95 its next wire-inserting movement and a pattern will thereby be produced in the fabric.

3. In a pile fabric loom of the type having a reciprocating member adapted during its movement in one direction to withdraw from 100 the fabric a pile wire that has been woven therein and during its next movement in the opposite direction to insert said pile wire in an open shed, pattern mechanism for controlling the operation of said member at 105 each wire-withdrawing movement to determine whether said member will be operative or inoperative to withdraw a pile wire whereby a pile wire will be inserted in or omitted from each shed and a corresponding 110 pattern produced in the cloth depending on the operation of the pattern mechanism.

4. In a pile fabric loom, the combination with means for withdrawing and inserting a pile wire, of pattern mechanism for controlling the operation of said means to render the said means inoperative to insert a wire at 115 predetermined times whereby a pattern will be produced in the fabric.

In testimony whereof, I have signed my 120 name to this specification.

HERBERT J. HOPE.
